(57) **CLAIM**

The ornamental design for a portable charging station, as shown and described.

DESCRIPTION

FIG. 1 is a front-side perspective view showing a portable charging station with its lid in the closed position;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plane view thereof;

FIG. 7 is a bottom plan view thereof;

FIG. 8 is a top right perspective view of a portable charging station shown with the lid in an open position shown in an environment of use;

FIG. 9 is a top right perspective view of the portable charging station in FIG. 1 with the lid in the open position;

FIG. 10 is a front elevation view thereof;

FIG. 11 is a rear elevation view thereof;

FIG. 12 is a left elevation view thereof;

FIG. 13 is a right elevation view thereof;

FIG. 14 is top plan view thereof; and,

FIG. 15 is a bottom plan view thereof.

The broken lines in the figures depict portions of the article and environmental structure which form no part of the claimed design.
